HAZEL GRACE TISDALL, OF TORONTO, ONTARIO, CANADA

DRESS PROTECTOR

Application filed March 9, 1931, Serial No. 521,164, and in Canada August 27, 1930.

My invention relates to improvements in dress protectors. The objects of the invention is to provide means which are readily attachable by pins or otherwise to the fabric of a dress on the lower margin of the sleeves and adjacent body portion of the dress, which means is of a sanitary material and is so formed as to detachably retain an absorbent pad and to provide a pad which can be conveniently inserted or withdrawn from the retaining means. Also to provide such a pad which may be stretched in manufacture so as to leave the side portions thinner than the intermediate portions, so as to prevent said pad from being bulky in front or to the rear of the arm and to dispose the greatest thickness of absorbent material directly between the arm and the body where the greatest exudation of perspiration takes place.

The invention consists essentially of a shield of non-absorbent material shaped to fit the lower portion of the arm hole of a dress, an absorbent pad shaped to substantially cover said shield, and means integral with the shield for retaining the pad in position, as will be more fully described in the following specification and shown in the accompanying drawings, in which:—

Fig. 1 is a general view of the invention.

Fig. 2 is a view of the pad removed from the shield.

Fig. 3 is a sectional view taken on the line 3—3 of Figure 1.

Fig. 4 is a sectional view of the pad taken on the line 4—4 of Figure 2 showing the diminishing thickness of pad adjacent its side edges due to shaping.

Fig. 5 is a general view of a modification.

In the drawings like characters of reference indicate corresponding parts in each figure.

The numeral 1 indicates generally a shield consisting of a pair of flaps 2 substantially semi-circular in form and curved along their upper border as at 3 to conform to the shape of the lower edge of the arm hole of a dress. The flaps are made of any suitable non-absorbent material and are connected together at their upper edges.

Secured adjacent the upper side edges of each flap as at 4 on their exposed sides are non-absorbent straps 5, which extend diagonally downwards in opposite directions and are connected at their lower ends to the lower side edges as at 6. The straps are preferably interlaced and form between them and each flap a pocket 7 for the reception of a pad 8. The pad 8 consists of a single sheet of absorbent material such as cotton batting or cellulose fibre of a predetermined thickness and substantially circular in form, which is folded upon itself about a centre line 9 and is then stretched to a progressively increasing length towards the side edges until the line of the fold is curved to conform to the curved upper edge 3 of the shield. The stretching of the absorbent material adjacent its side edges reduces its thickness as shown in Figure 4, to less than the thickness of material about the vertical centre of the pad. The pad 8 is preferably covered with a sheet of light open fabric 10, such as cheese cloth, to prevent the disturbance of the exposed surface of the pad, which fabric is folded on the bias and is stretched about the line of fold as shown in Figure 2 to conform to the shape of the pad 8. The borders of the fabric 10 are turned in over the edges of the pad 8 as at 11 and are preferably lightly secured in position with a suitable adhesive.

In the modification shown in Figure 5 the pockets 7 are formed by attaching substantially horizontal and spaced straps 12 and 13 respectively to opposite sides of each flap 2 and attaching spaced vertical straps 14 to the lower edges of the flaps and to the strap 12.

It will be obvious that any reticulated material can be used and serve a similar purpose to the straps.

Having thus described the several parts of my invention I will now briefly explain its use.

The shield 1 is placed in position in the arm hole of a garment with one flap 2 in the sleeve and the other inside the garment body. The shield will preferably be secured by stitching or with a pair of pins. Prior to putting on the garment a pad 8 is put in position by

inserting its lower ends into the pockets where it is retained by the straps. Perspiration from the arm pit will be readily absorbed by the pad and retained therein, thus preventing 5 any moisture from reaching the fabric of the garment. When the garment is removed, the pad is withdrawn and the shield may be wiped down with a damp cloth or sponge, thus rendering it free from body odours and 10 making it sanitary, ready for the insertion of a new pad.

What I claim as my invention is:

1. A dress protector comprising a non-absorbent shield adapted to be supported in 15 a garment and having opposed flaps provided with straps extending across their points and connected to the borders of said flaps to define a pair of open topped pockets, said pockets being adapted to receive a folded pad of 20 absorbent material and to leave the major portion of said pad and its borders exposed to the wearer's body.

2. A dress protector as claimed in claim 1 in which the straps are spaced apart a distance greater than the width of said straps 25 whereby easy access is obtained to the points of the pad for washing and drying.

Dated at Detroit, Michigan this 25 day of Feb., 1931.
